UNITED STATES PATENT OFFICE.

HANS STOCKMEIR, OF BALTIMORE, MARYLAND.

MUSICAL INSTRUMENT.

No. 809,539.

Specification of Letters Patent.

Patented Jan. 9, 1906.

Application filed September 18, 1905. Serial No. 278,906.

To all whom it may concern:

Be it known that I, HANS STOCKMEIR, a citizen of the United States, residing at Baltimore, in the State of Maryland, have invented 5 a new and useful Musical Instrument, of which the following is a specification.

This invention relates to musical instruments, and has for its principal object to provide a string instrument of that general type 10 wherein the strings are set into vibration by picking.

A further object of the invention is to provide a musical instrument of this character in which the picks are operated from a key-board of the general type ordinarily employed 15 on pianos or organs.

A still further object of the invention is to provide an improved form of pick of such nature as to engage with and positively move 20 the string on the depression of the key and moving idly past the string when the key is released.

With these and other objects in view, as will more fully hereinafter appear, the invention 25 consists in certain novel features of construction and arrangement of parts herein-after fully described, illustrated in the accompanying drawings, and particularly pointed out in the appended claims, it being understood 30 that various changes in the form, proportions, size, and minor details of the structure may be made without departing from the spirit or sacrificing any of the advantages of the invention.

35 In the accompanying drawings, Figure 1 is a perspective view of a musical instrument constructed in accordance with the invention. Fig. 2 is a vertical section of the same on the line 2 2 of Fig. 1. Fig. 3 is a sectional 40 perspective view of the front portion of the instrument. Fig. 4 is a detail perspective view of one of the picks and its actuating-key. Figs. 5 and 6 are detail views of a pick, showing the same in different positions, respectively.

45 Similar numerals of reference are employed to indicate corresponding parts throughout the several figures of the drawings.

50 The instrument forming the subject of the present invention is preferably of the portable type and is provided with a suitable base 10 and vertical walls 11, which may be formed of any suitable material, preferably 55 wood. At the rear of the frame is a cross-far 12, constituting a wrest-plank for the re-

ception of tuning-pins 13, and at the front is a cross-bar 14, carrying pins 15, to which the front ends of the strings 16 are secured, said strings passing through suitably - inclined 60 openings in a bridge-piece 17. The cross-bars and side walls of the frame serve to support a sounding-board 18, which may be of any ordinary construction.

The number of strings in the instrument 65 may vary; but in the preferred construction the number of strings is equal to the number of keys in an ordinary piano and each is controlled from a separate key 19, the keyboard being arranged at the front of the instrument 70 and resembling the ordinary piano - key, so that any piece of music written for the piano may be played on the instrument by any performer without instructions.

The keys 19 are secured each to the top of 75 a pin 20, the lower end of which has a ball-and-socket connection with a lever 21, that is pivoted in a hanger 22, secured to the key-frame 23, and said lever carries a small leaf-spring 24, which by engagement with the under side of the key-frame serves to maintain the key in elevated position. The rear end of each lever 21 has a ball-and-socket connection with a vertically-movable pin 26, the upper end of which is connected by a link 27 to 80 the approximately horizontal arm of a bell-crank lever 28. To the upper end of the vertical arm of the bell-crank lever, which extends through an opening in the sounding-board, is pivoted a picking-finger 30, that is 85 provided with a flange 31, encircling a portion of the upper end of the bell-crank lever and forming a rule - joint that will permit yielding in but one direction. This arm of the bell-crank lever also carries a damper-arm 32, to which is secured a small damper 33, formed of felt or other suitable material and normally in engagement with the string when the picking-finger is in a position at 90 rest. On downward pressure on the key pin 95 26 is moved upward and the bell-crank lever is moved from the position shown in Fig. 5 to the position shown in Fig. 6, the damper moving away from the string and the picking-finger engaging said string and setting the 100 same into vibration. When the pressure on the key is relieved, spring 24 serves to restore the parts to initial position, and during this movement the picking-finger will turn freely on its pivot and will not set the string 105 into vibration during the return movement. During this return movement a bridle 34,

which is connected to the flange 31 of the picking-finger, serves to move the latter to proper position with respect to the bell-crank lever 28. This bridle, which may be formed 5 of leather or other suitable material, is secured at one end to a pin 35 and its opposite end passed through a suitable groove or slot formed in the vertical arm of the bell-crank lever and is attached to the flange 31. At 10 the completion of the return movement of the picking-finger the damper 33 comes into contact with the string.

With an instrument constructed in accordance with this invention any composition 15 written for the piano may be readily played, the effect being similar to that produced by a harp or zither in accordance with the character and tuning of the strings.

Having thus described the invention, what 20 is claimed is—

1. In a musical instrument, the combination with a sounding-board and strings, of a keyboard, key-actuated levers operable from the keyboard, a pivotally-mounted bell-crank 25 lever having one of its arms connected to one of the levers, a picking-finger carried by the opposite arm of the bell-crank lever, the finger being movable with the lever in one direction, and being movable independently of

the lever in the opposite direction, and a bridle 30 for insuring return movement of said finger.

2. In a musical instrument, the combination with the sounding-board and strings, of a picking-finger, a lever carrying the same, said finger having a laterally-extended flange 35 for engagement with the lever in order to limit pivotal movement of the finger in one direction, and a bridle for insuring return movement of the picking-finger to initial position. 40

3. In a musical instrument, the combination with the sounding-board and strings, of a key-actuated lever, a bell-crank lever operatively connected to said lever, a picking-finger pivotally mounted on said bell-crank lever, and arranged to positively engage with the string during movement in one direction, and moving freely past the string in the opposite direction, a bridle for insuring return of the picking-finger to proper position, and a 45 damper also carried by said bell-crank lever. 50

In testimony that I claim the foregoing as my own I have hereto affixed my signature in the presence of two witnesses.

HANS STOCKMEIR.
